AUTOMOTIVE ENGINE TESTER

Dennis J. Lowery and Vincent H. Rose, Grand Junction,
Colo., assignors to Dixson, Inc., Grand Junction, Colo.

Filed Sept. 26, 1973, Ser. No. 400,891

Term of patent 14 years

Int. Cl. D10—04

U.S. Cl. D10—46

FIG. 1

FIG. 2

FIG. 3

FIG. 4

FIG. 5

FIG. 1 is a top plan view of an automotive engine tester showing our new design with the various connecting leads shown broken away for ease of illustration;

FIG. 2 is a left side elevational view thereof, the right side being a mirror image thereto and the leads omitted for ease of illustration;

FIG. 3 is a front elevational view of FIG. 2;

FIG. 4 is a rear elevational view of FIG. 2; and

FIG. 5 is a bottom plan view of FIG. 2.

We claim:

The ornamental design for an automotive engine tester, as shown and described.
